UNITED STATES PATENT OFFICE.

PAUL LOUIS JOSEPH MIGUET, OF ST.-JULIEN-DE-MAURIEENNE, FRANCE, ASSIGNEE TO
SOCIETE ELECTROMETALLURGIQUE DE MONTRICHER, OF ST.-JULIEN-DE-MAURIEENNE, FRANCE.
OPEN ELECTRIC FURNACE.

Application filed September 28, 1926, Serial No. 128,539, and in France December 28, 1925.

This invention relates to improvements in open electric furnaces.

The object of the invention is to provide a mounting and cooling means which shelter the exterior of the electrode the connections and the superstructure of the furnace from the flame fumes and dust of manufacture.

The invention further relates to a system of lateral electro-mechanical connections for the continuous electrode for effecting the above-mentioned mounting and cooling.

The advantages of the invention are as follows:—

(a) The suppression of the usual metal coating of the electrode when this is indeformable,

(b) The limiting of the importance of the conductors and connections of the electrodes to electro-mechanical considerations,

(c) A mounting, operation and control of the superstructure apparatus independently of the products.

The invention will be described with reference to the accompanying drawings:—

Fig. 1 is a sectional elevation showing the mounting and cooling arrangement.

Fig. 2 shows two half horizontal sections of same.

Fig. 3 is a sectional elevation of the lateral electro-mechanical connections.

Fig. 4 is a plan of same.

Referring to Figs. 1 and 2 a bronze conducting screen 1 affixed at 2 to an iron tube 3 carried by a table 4, is formed by jointed sectors which are held in position by bolts 5 and individually cooled by water tubes 6 branching out from the current supply arms 7, the screen extending nearly to the electrode adjacent to the mass 8 to be treated and a ring of asbestos 9 passing round the electrode 10 helping in protecting the flexible leads 11 and keeping the temperature from becoming high, a cast jacket 12 is affixed to the tube 3 at 13 and is also built up in sections jointed together as before but only placed side to side and individually cooled by water flowing through tubes 14 forming a water seal on their medial lines 15 which prevents gas fumes and dust from reaching the aspirator 16 except through two contractions at 17 and two expansions

at 18 in chambers having baffles 19 formed with moderating and eddy holes 20.

The first contraction serves to create a gaseous screen moving at such a speed that with the help of an exterior baffle 21 nothing can escape to the aspirator, the second contraction serving to renew the vein in contact with the cast wall of material so that the cooling shall be complete before collecting.

Referring to Figs. 3 and 4 bronze contact plates 22 cooled by water circulating in tubes 23 are formed with an inclined side 24 furnishing means for individual contact or not between the electrode 25 and a common demagnetized steel ring 26 by means of a left and right handed screwed rod 27 operated from the table 28 by a limiting screw 29 which screws into bronze balls 30 rotatable in bearings 31 and 32 respectively. Flexible connections 33 and a lifting rod 34 are connected to the holder without interfering with its operation.

The substitution for another reason cannot take place without a modification being made in the shape of the inclined side 24 to allow for the reversing of the plates necessitated by the larger diameter at the entering end.

What I claim as my invention and desire to protect by Letters Patent is:—

1. A mounting arrangement for electrodes of open electric furnaces, comprising a conducting screen surrounding the electrode and extending adjacent to the mass to be treated in the furnace, means for supporting said screen, means for supplying electric current to said screen, connections between said screen and said electrode, annular supporting means for the electrode and means acting on said supporting means to allow an axial adjustment of said electrode relatively to said supporting means.

2. A mounting arrangement for electrodes of open electric furnaces, comprising a conducting nonmagnetizable screen surrounding the electrode, means for supporting said screen, means for cooling said screen, connections between said screen and said electrode, annular supporting means for the electrode, and means for allowing an axial adjustment of said electrode relatively to said supporting means.

3. A mounting arrangement for electrodes of open electric furnaces comprising a conducting screen surrounding the electrode, means for supporting said screen, means for cooling said screen, water-cooled means surrounding said screen for collecting and cooling gas, fumes and dust escaping out of said furnace, annular supporting means for the electrode and contact plates interposed between said electrode and its supporting means, said contact plates being electrically connected to said screen and means allowing an axial adjustment of said electrode relatively to its supporting means.
4. A mounting arrangement for electrodes of open electric furnaces, comprising a conducting screen, formed by water-cooled jointed bronze sectors and surrounding the electrode means for supplying electric current to said sectors, connections interposed between said sectors and the electrode and adjustable supporting means for the electrode.
5. A mounting arrangement for electrodes of open electric furnaces, comprising a conducting screen surrounding the electrode and extending adjacent to the mass to be treated in the furnace refractory jointing means interposed between the lower part of said screen and said electrode and adjustable supporting means for the electrode.
6. A mounting arrangement for electrodes of open electric furnaces comprising a water-cooled conducting screen means for supplying an electric current to said screen, connections between said screen and the electrode, adjustable supporting means for the electrode, a water-cooled annular aspirator surrounding the upper part of said screen, baffles disposed at the outside of means for supplying electric current to said screen and forming a conduit for directing the gaseous products and the dust escaping from the furnace towards said aspirator and perforated partition walls disposed transversely to the flow of said products and dust allowing their cooling before collecting and adjustable supporting means for the electrode.
7. A mounting arrangement for electrode of open electric furnaces, comprising water-cooled wedge formed contact plates arranged around the electrode, flexible connecting means for supplying current respectively to said contact plates, a closed holder disposed around and at some distance of said electrode, whereon said contact plates bear, means for displacing said contact plates relatively to said holder in order to allow an axial adjustment of said electrode.
8. A mounting arrangement for electrodes of open electric furnaces comprising water-cooled wedge-formed contact plates arranged around the electrode and engaged between said electrode and a closed ring, adjustably supported, left and right handed screwed rods vertically disposed respectively between said contact plates and said ring, means for acting respectively on said rods for displacing the corresponding contact plates relatively to said ring in order to allow an axial adjustment of said electrode and flexible connections for supplying current to said contact plates.
9. A mounting arrangement for electrodes of open electric furnaces, comprising a water-cooled conducting screen, means for supplying an electric current to said screen, a closed ring surrounding and disposed at some distance from the electrode, adjustable means for supporting said ring independently of said screen, water-cooled wedge-formed contact plates arranged around said electrode and engaged between said electrode and said ring, connections between said screen and said contact plates and means for displacing each of said contact plates relatively to said ring, in order to allow an axial adjustment of said electrode relatively to its support.

In witness whereof I affix my signature.
PAUL LOUIS JOSEPH MIGUET.
